UNITED STATES PATENT OFFICE.

CHARLES BECKER, OF MILWAUKEE, WISCONSIN.

BUILDING-BLOCK.

1,186,537.

Specification of Letters Patent. Patented June 13, 1916.

Application filed July 26, 1915. Serial No. 41,853.

To all whom it may concern:

Be it known that I, CHARLES BECKER, a citizen of the United States, and resident of Milwaukee, in the county of Milwaukee and 5 State of Wisconsin, have invented certain new and useful Improvements in Building-Blocks; and I do hereby declare that the following is a full, clear, and exact description thereof.

10 This invention relates to the subject of building blocks, and has for its main object the production of building blocks having their upper and lower surfaces provided with alternating grooves and projections 15 which are so disposed that when the blocks are superimposed, said blocks will have a firm interlocking engagement that will prevent relative slippage of the blocks.

Simple and thoroughly practical embodiments of blocks constructed in accordance 20 with this invention are shown in the accompanying drawings, wherein—

Figure 1 is a plan view of a portion of a wall formed of blocks made in accordance 25 with this invention. Fig. 2 is a sectional view taken on the line 2—2, Fig. 1, an additional brick being shown on top of the bricks shown in Fig. 1 to illustrate the interlocking engagement at the corner.

30 The improved building blocks forming the subject-matter of this application may be formed of any suitable material and shaped in accordance with the type of wall or other structure they are to be used in forming, the 35 essential feature of the blocks being that their upper and lower surfaces be of such a nature that when the blocks are superimposed, they will have a firm interlocking engagement that will prevent the blocks relatively slipping in any direction.

40 Two forms of the improved blocks have been shown in the accompanying drawing, the blocks designated by the character A being primarily intended for use in connection 45 with straight work, and the blocks designated by the character B being intended for use in connection with angular work, such as corners and the like.

The blocks A have their upper and lower 50 surfaces provided with alternating projections 1 and grooves 2, the grooves and projections being of a substantially V-shape with their apexes at the longitudinal center of the blocks, and said grooves and projections 55 are preferably rounded. The V-shape shown is preferred as such causes the blocks

to have a firm interlocking engagement when superimposed that will effectively prevent relative slippage of the blocks either longitudinally or laterally.

60 The blocks B have their upper and lower surfaces provided with grooves and projections of the same character as those formed on the blocks A, but said grooves and projections of blocks B are arranged in two sets 65 on each surface of the blocks, the set of grooves and projections designated generally by the character 3 being arranged so that their apexes extend transversely of the blocks, and the set of grooves and projections 70 designated generally by the character 4 being arranged so that their apexes extend longitudinally of the blocks. The blocks B, as aforesaid, being primarily intended for angular work, such as corners, it will be seen 75 that when assembled in connection with the blocks A, the sets of grooves and projections 3 form a continuation of and interlock with the grooves and projections of said blocks A, and the sets of grooves and projections 4 80 are in position to interlock with other blocks A that are disposed at right angles to the first mentioned blocks A.

Figs. 1 and 2 of the drawings illustrate 85 the relative arrangement of the blocks A and B when in practical use, and by referring to said figures it will be seen that the blocks in their straight courses and in their angular courses have a firm interlocking engagement. Obviously such engagement 90 may be made a permanent one by the use of mortar or other binding material.

I claim as my invention:—

1. A building block having its top and bottom surfaces each provided with regularly spaced alternating grooves and projections, that are V-shaped in plan and V-shaped in cross section with their respective sides mutually merged together and having their apexes alined at the center of the said 100 surface.

2. A building block having its top and bottom surfaces provided with alternating, regularly spaced grooves and projections that are V-shaped in plan with their apexes 105 alined at the centers of the said surfaces, said grooves and projections being arranged in two sets on each surface of the block, one set having their apexes in a line extending longitudinally of said surface and the other 110 set having their apexes in a line extending transversely of said surface.

3. A building block having its top and bottom surfaces provided with alternating, regularly spaced grooves and projections that are V-shaped in plan with their apexes aligned at the centers of the said surfaces, said grooves and projections being arranged in two sets on each surface of the block, one set having their apexes in a line extending longitudinally of said surface and the 10 meeting edges of the sets forming a third

set V-shaped grooves on one side of the longitudinal centers of the surfaces.

In testimony that I claim the foregoing I have hereunto set my hand at Milwaukee, in the county of Milwaukee and State of Wisconsin, in the presence of two witnesses.

CHARLES BECKER.

Witnesses:

ADOLPH JENNERJOHN,
CHARLES H. STROTHMEYER.
